UNITED STATES PATENT OFFICE

LOUIS N. D. WILLIAMS, OF OGONTZ, PENNSYLVANIA, AND HARRY SWINGLEHURST, JR., OF BROOKLYN, NEW YORK, ASSIGNORS TO SCOTT & WILLIAMS, INCORPORATED, OF NEW YORK, N. Y., A CORPORATION OF MASSACHUSETTS

LOOP RETAINER AND MECHANISM THEREFOR

Application filed September 11, 1928. Serial No. 305,206.

This invention relates to looping machines which are used for uniting knitted webs, particularly the toe pockets of seamless stockings produced on circular knitting machines, and it is concerned especially with a retainer for holding the webs in place during folding of the point carrier and with a mechanism for manipulating such a retainer automatically.

In a preferred type of looping machine the webs to be united are placed on a diametrically divided ring, the loops being carried on a peripheral series of points on the two segments of the ring. The preferred type of machine has provision for automatically folding one segment of the ring about a diametral axis to bring the points on that segment into register with the points on the stationary segment. The loops carried by the points of the folded segment are then stripped from those points by an automatic mechanism and are slipped onto the registering points of the other segment. This operation is sometimes spoken of as doubling the loops. The movable segment is then swung back to its original position and the ring is rotated to present the loops on the points of the other segment successively to a sewing mechanism which unites the two loops on each point to each other and to the other loops.

The type of looping machine now preferred is described and illustrated in the Patent 1,715,400 granted on the application of Louis N. D. Williams, Serial Number 160,165, filed January 10, 1927.

It has been found in the use of such looping machines that there is a tendency on the part of the loops on and near the end points of each segment of the carrier ring to slip from their points during the folding of the one segment upon the other.

To obviate this difficulty, retainers have been employed. These are inserted between the end points of the two segments. When the fabric is folded the yarn looped on the end points is engaged by the retainers and is held on the end points. The retainers are then removed to permit the stripping operation.

The retainers known before this time have been manipulated by hand thus adding to the total time required for each looping operation. Furthermore, the design of the retainers themselves has not been altogether satisfactory. A manually operated retainer is shown in the patent to Butz 1,068,853.

The present invention relates in particular to the retention of the fabric upon the points of a foldable point carrier during the folding thereof preparatory for the looping operation, to an improved retainer and to an automatic mechanism for moving retainers into and out of their functioning positions at the proper time in the cycle of operations of the looping machine.

The objects of the invention are

(1) To improve the design of the retainer itself;

(2) To provide an automatic mechanism for moving the retainers to and from their functioning position at the desired points in the cycle of operation of the looper;

(3) To relate the operations of the retainer to those of the looping machine in such a way that the total time required for the cycle of operation of the looping machine will not be increased by reason of the use of retainers;

(4) To provide an automatic retainer-manipulating mechanism which conveniently may be applied to a looping machine already built;

(5) To provide an automatic retainer-manipulating mechanism of simple construction, reliable in its functioning.

The invention is described hereinafter and shown in the accompanying drawings as applied to the looping machine which is shown in the Patent 1,715,400 of Louis N. D. Williams, mentioned above. It is understood that while the invention is so described it is not limited in its applicability to that particular looper but that it is capable of use with other types of such machines.

In the drawings—

Figure 1 is a top plan view of a looping machine, stripped of certain parts not necessary for a description of the novel features here disclosed and showing the loop retainers and their operating mechanism;

Figure 2 is a similar view of the same, showing the position of the parts during the stripping operation;

5 Figure 3 is an elevational view of the same machine with the certain parts removed, the view being taken from the direction at right angles to that of Figure 1;

10 Figure 4 is a view in side elevation showing details of the mechanism for moving the retainer arms.

Figure 5 is a view taken on the line 5—5 of Figure 1 showing the mechanism for removing the retainers during the stripping operation;

15 Figure 6 is a detail plan view showing the relation of a retainer to the points of the ring before the ring is folded;

20 Figures 7, 8 and 9 are elevational views taken on the line 6—6 of Figure 6 showing an end point of the stationary segment and a retainer in functioning position to illustrate the manner in which the loops on the end points are retained thereon as the ring is folded;

25 Figures 10, 11 and 12 are elevational views looking toward the ring from the outside along the axis of folding showing the relation of the fabric, points and retainer before, during and at the completion of the folding.

30 The bed plate 15 of the looping machine is centrally apertured to receive a cylindrical carrier 16 upon which the transfer ring R is supported in such a way as to be rotated with the carrier by a ratchet mechanism, not shown. This ratchet mechanism is shown in U. S. patent to Williams 1,315,064.

35 The transfer ring R, so called because it is used to transfer the fabric from the knitting machine to the looping machine, consists of two segments 17, 18. Each segment carries a number of upstanding quills or points P extending circumferentially around its periphery, the number and spacing of the points being the same on each segment. The 40 segment 18 is held stationary with respect to the carrier 16 while the segment 17 may be swung upwardly about a diametral axis by reason of the hinges 19, 20. When swung through 180° the segment 17 rests over the 45 segment 18 with the points P of the two segments in vertical alignment. In some machines, the points overlap slightly. For the present purpose, the expression "in register" or the like is used to describe generically the 50 relation of one set of points to the other set when the segments are brought together to permit a transfer or doubling of the loops on one to the other.

55 The sequence of operations of the machine is determined by a cam drum C having a number of inter-related cam rings. On its top is a plate cam 21 with lugs 22, 23. Co-operating with this plate cam is an arm 24 having pallet-like projections 25 engaging the plate cam and a pin 26 which takes into a

slot in a horizontally rocking lever 27. Lever 27 has a finger 28 adapted to enter an opening in the segment 17 of ring R. When the plate cam 21 is in the position shown in Figure 1, the lug 22 rocks arm 24 to a position which causes lever 27 to be swung toward the ring R so that the finger 28 enters the opening therein.

60 Lever 27 is adapted to be swung in a vertical arc by means of an arm 29 secured thereto and also to a short shaft 30. The shaft 30 is mounted in a fixed bearing 31 on the frame of the machine and has at its outer end a pinion 32 which is in mesh with a segmental gear 33 on the end of an arm 34 (Fig. 3) 65 rockable in a vertical plane. A pin 35 on arm 34 and eccentric of its rocking axis engages in a cam groove 36 in the side face of the cam drum C and imparts to arm 34 a rocking movement when moved by the sloping portion 37 of groove 36.

70 The cam lug 22 and the portion 37 of groove 36 are so related angularly that immediately after the action of lug 22 in causing finger 28 to engage segment 17, the portion 37 comes opposite pin 35 and rocks arm 34 whereupon the arms 29 and 27 are swung upwardly folding segment 17 over upon segment 18 as shown in Fig. 2.

75 Following the folding of the segment 17 to bring the points on it into register with the points on segment 18, the stripping mechanism is brought into play. Within the segments of the ring R are axially movable segments 90 peripherally notched to provide fingers between the points P. When they are moved toward the tips of the points the fingers and the inner end of the notches engage the loops and strip them from the points. The doubling of the loops is accomplished 80 by moving the stripper 90 within segment 17 downward toward the tips of the points when the segment 17 is in the position shown in Fig. 2. By this, the loops on the segment 17 points are slipped or doubled onto the 85 registering points on the segment 18.

90 The mechanism for moving the stripper of segment 17 consists of a hooked lever 40 pivoted on a bracket 55 on the machine frame and rocked by compound levers 41, 42 which derive their motion respectively from that of pins 43, 44 which engage grooves 45, 46 in the cam drum C. The sloping portions of these grooves are so disposed angularly with respect to portion 37 of groove 36 that the 95 stripper-engaging member or actuator 47 is moved downwardly to meet the stripper on segment 17 as soon as the latter has been folded onto segment 18.

100 The loop retainers and the automatic mechanism for moving into position between the end points on segments 17 and 18 will now be described.

105 The retainers 50 and 51 are formed as angle pieces secured by removable screws to 110

separate arms 52 and 53 which are arcuate in shape and are pivoted on a rod 54 which is mounted in spaced offsets on the brackets 55 upon which the hooked lever 40 is supported.

5 The arms 52 and 53 are adapted for movement axially along the rod 54 as well as for swinging about it. Springs 56 secured at one end to a fixed part 57 of the machine frame tend to hold the arms downward as in Fig. 1 where the arms, 52, 53 are in a horizontal plane thus putting the retainers in position between the end points of the segments. Other springs 56' between the offset portions of the bracket 55 and the pivot portions of arms 52, 53 and surrounding the rod 54 urge the arms toward each other and toward the mid-portion of rod 54.

Suspended from the hooked lever 40 which carries the stripper actuator 47, is a member 58 having a wedge shaped portion 59 and a narrower extension 60. (See Figure 5). When the hooked lever is in its position of rest as in Figs. 1 and 4, the extension 60 is between arms 52, 53 and serves to space them 20 to the proper extent to put the retainers in correct position radially with respect to the points, and also it provides an entrance for the wedge portion 59 (Fig. 5).

When the hooked lever moves toward stripping position the wedge portion separates arms 52 and 53 by sliding them along rod 54. Thus by the time the stripper actuator 47 meets the stripper 90 on the segment 17 the retainers have been displaced radially sufficiently to clear the outside of the points (see Fig. 2). The stripper then is able to slide the end loops onto the segment 18 points along with the other loops. This removal of the retainers is necessary since, after folding, the retainers lie close to the end points (see Fig. 12) and would interfere with the last part of the downward movement of the stripper.

When stripping is complete, the hooked lever is restored to its upper or rest position by the cam grooves 45, 46 and, in doing so, the wedge-shaped portion 59 is lifted and arms 52 and 53 return to their central position as in Fig. 5 under effort of spring 56' putting the retainers again in position between the points.

Since the presence of the retainers between the points has no function after the folding is completed, and since it would interfere with the subsequent rotation of the carrier 55 16 and ring R in presenting the doubled loops to the sewing apparatus, mechanism is provided to lift the retainers away from the ring as soon as the latter is unfolded and restored to the position shown in Figure 1. The unfolding occurs immediately after the stripping when cam drum C presents to the pin 35 the upwardly sloping portion (not shown) of groove 36. It may also be noted at this point that when segment 17 is restored to the position shown in Fig. 1, cam lug 23, properly

positioned on plate 21 for this purpose, rocks arm 24 to disengage finger 28 from the opening in ring R.

The mechanism for putting the arms 52, 53 in raised position and for moving them from that position to their functioning position between the end points just prior to folding of ring R, will now be described.

A bar 61 extends transversely beneath the ends of arms 52, 53 near rod 54 and is mounted by an off-set to swing about an extension of rod 54 projecting beyond bracket 55. An upright rod 62 having an angled or inclined piece 62' connects this bar 61, at a point eccentric of its axis on rod 54, with a member 63 secured to a so-called starting lever 64 and transverse thereof. The starting lever 64 is pivoted on a fixed part of the frame.

A pair of jointed horizontal links 65, 66 connect lever 64 with the cam drum C, link 65 being secured to lever 64, and link 66 being pivoted at 67 on a fixed part of the frame, not shown.

On the cam drum and in the same horizontal plane as link 66 is a lug 68. This lug is so positioned on the drum that it engages link 66 and swings its engaging end outward from the drum at the same time that lug 22 is swinging arms 24 and 27 to put finger 28 in engagement with segment 17, preparatory 95 for folding of the ring.

The outward movement of the engaging end of link 66 swings the link 65 and thereby tilts the starting lever 64 in a direction causing a downward movement of the rod 62. The result is that bar 61 is dropped sufficiently to permit the arms 52, 53 to swing downward under the influence of springs 56 putting the retainers in functioning position as in Figure 1.

A latch 69 is pivoted on the frame (not shown) to lie tangent to the cam drum just above lug 68 and has a portion 70 bent away from the drum to drop into engagement with the link 66 after the lug 68 has been rotated sufficiently to clear the end of the link. The latch therefore holds the link 66 away and through the linkage described above, it keeps bar 61 in its lower position.

When the ring is unfolded after the stripping operation, a pin 71, properly positioned on the cam drum to come into the region of latch 69 at about the time that lug 23 is moving finger 28 out of the opening in segment 17, rides under latch 69 and lifts it away from link 66 permitting the link end to move toward the drum. Through the linkage 66—62, the movement of the link 66 causes the bar 61 to be raised, carrying with it the retainer arms 52, 53, this movement being caused by reason of the fact that the lever 64 is spring-stressed in a direction such that it tends to rock the link 66 toward the cam drum. The precise location of pin 71 may be determined by a consideration of the fact that the arms 130

52, 53 may be raised as soon as the segment 17 has been swung toward unfolded position sufficiently to provide a clear space between the end points of the segments for the passage upward of the retainers.

It is to be noted that at the forward end of lug 68 is a small cam or lug 72. This corresponds to the starting pin 87 in the Williams Patent 1,715,400. Upon the initial movement of the cam drum in a cycle of operations, the starting lug 72 moves link 66 a slight amount causing lever 64 to rock slightly to the left as viewed in Fig. 3. This moves pin 73 on lever 64 from beneath the corner 74 of the edge of carrier 16 permitting the carrier to drop in order to put ring R in position with respect to the sewing mechanism. It is noted that the carrier edge 75 is inclined upwardly from the corner 74.

During the last part of the rotation of the cylinder, while the segment 17 is being rapidly stepped past the sewing mechanism, this edge 75 rides on pin 73 and thereby the carrier is restored to upper position to make easy the removal of ring R. This is all described in the Williams Patent 1,715,400.

The retainer 50 (Sheet 5), (and, of course, retainer 51 also) has a part extending between the end points of the parts of the foldable point carrier R. This part comprises a throat 502 which is at the level of the tips of the points to permit the end point P¹⁷ to swing about into registry with point P¹⁸, and a portion 503 extending above and below the level of the tips on the fabric side of the points. This portion 503 recedes on its forward edge 504 from the upper edge and may be curved although many variations of the curvature are possible as will be apparent when its purpose is understood. A strictly vertical forward edge is possible but is not preferred.

It is the portion 503 with the edge 504 which acts on the yarn to keep the end loop 45 on the points. The action will be understood from a consideration of Figures 6 to 12.

These figures show the end points P¹⁷ and P¹⁸ at one juncture of the ring segments, the retainer 50 and one wale 80 of the fabric. For convenient reference, the loop on point P¹⁸ is designated as 81 and the loop on point P¹⁷ as 82. The portion of yarn 83 between the end loops 81 and 82 does not appear in Fig. 7 but Figures 6 and 9 show it to be beneath the retainer portion 503.

Figure 8 shows the manner in which the yarn portion 83 rides up on the sloping edge 504 as the segment 17 with end point P¹⁷ is swung over onto segment 18. During the first part of the swinging of segment 17, the yarn portion 83 assumes a diagonal position across the edge 504 and partly folds over this edge. As it rides up the edge 504, this yarn portion is held away from the points

laterally. Figure 8 is a view at the instant P¹⁷ comes into register with P¹⁸. The end of yarn portion 83 toward loop 82 has come up from in back of the retainer end 503 (compare Fig. 6) and is lying along the edge 504. Immediately thereafter, as shown in Figure 9, the portion 83 slips over the upper tip of the retainer end 503 thus bringing all the fabric to one side of the retainer. The retention could be obtained without having the yarn portion 83 finally slip over the tip of the end portion 503 by having the tip higher. The yarn then would merely fold over the end portion 503 and would be given a greater stretch. The tip shown is more satisfactory.

The action of the end 503 in preventing loops 81 and 82 from slipping from their points is perhaps best understood by visualizing the changes from the Fig. 6 view. As P¹⁷ moves upward, yarn portion 83 must move to the left under the guidance of edge 504. As yarn portion 83 moves to the left, the yarn in loops 81 and 82, is drawn tightly against the points P¹⁷ and P¹⁸. In addition to the frictional resistance thereby effected, the yarn is held out laterally from the points and away from the tips toward which it otherwise would be drawn. Other actions may be present. This is not intended to be an exhaustive statement of the theory of operation.

Figure 2 shows the condition of the yarn portions when the folding is partly completed and further illustrates the positive action of the retainer end 503 in resisting the tendency of the yarn to be drawn off the points when they are separated abnormally during the swinging of segment 17.

From Fig. 2 it is apparent that while preferably the throat 502 should be even with the tips of the points P, it could be slightly above without interfering with the swinging of point P¹⁷ since there may be a slight clearance between the tips when folded. It could also be below the tip level, the only consideration being that if dropped too far the end 503 might be too low to retain the loop 82 on point P¹⁷.

The important part of the retainer is the end 503. Experiment will readily show the distance it must extend above and below the level of the tips when in register to keep the loops on the points. This reference level, of course, is not a geometrical plane except possibly where the points meet tip to tip when folded. When the tips overlap or when they do not meet when folded onto register with each other, the level will be between the planes of the tips.

As distinguished from former retainers which were simple points projected horizontally between the upright end points, the present retainer is characterized by the fact that it is thin and flat so that it may extend between the points and present a forward

edge 504 of considerable extent in the direction of the end points. This edge holds the portion of thread, between the loops impaled on the end points, laterally against the points and is suitably shaped to act as a cam or guide so that the thread may move along it and still be held laterally away from the points. In this way the loops are held from slipping off the points. The end 503 of the retainer may be variously made to provide such a forward edge due to its considerably greater height than thickness.

The curve of edge 504, as shown, is preferable since it gives a gradual displacement of yarn portion 83 during the folding. The curved top of end 503 also permits easy movement of the yarn over it in the change from the Fig. 8 to the Fig. 9 position.

The dotted outline in Fig. 9 illustrates the withdrawal of the retainer radially to permit the stripper 90 to move downward to double the loops. Other directions of movement of the retainer are possible just so it is moved out of the way of the stripper.

The description and claims here are phrased in terms of a vertical arrangement of the points as that is the preferred and, in fact, the only form of looper in actual use, having a foldable carrier. It will be understood however that the invention is not limited to use with vertically arranged points and that the claims are not to be read as excluding other arrangements, such words as "above", "below", "upwardly" and the like being used in a relative sense.

We claim—

1. In a looping machine, a foldable segmental point carrier and a loop retainer adapted to extend transversely of said carrier between the end points of the carrier segments, said retainer comprising an end portion adapted to extend on the fabric side of the points above and below the level of the tips of the points.

2. In a looping machine, a foldable segmental point carrier and a loop retainer adapted to extend transversely of said carrier between the end points of the carrier segments, said retainer comprising an end portion adapted to extend on the fabric side of the points above and below the level of the tips of the points and having its forward edge receding from the upper edge.

3. In a looping machine, a foldable segmental point carrier and a loop retainer adapted to extend transversely of said carrier between the end points of the carrier segments, said retainer comprising an end portion adapted to extend on the fabric side of the points above and below the level of the tips of the points and having its forward edge receding from the upper edge on a curved line.

4. In a looping machine, a foldable segmental point carrier and a loop retainer

adapted to extend transversely of said carrier between the end points of the carrier segments, said retainer comprising an end portion presenting a forward edge over which the thread portion between the loops on the end points extends during folding whereby to draw the said loops laterally against the end points.

5. In a looping machine, a foldable segmental point carrier and a loop retainer adapted to extend between the end points of the carrier segments, said retainer having an end portion with a forward edge for engaging the thread portion between the loops on the end points and guiding it laterally away from the points while the segments are being folded.

6. A loop retainer for use with a looping machine comprising a throat and an end portion adjacent said throat and extending upwardly therefrom.

7. A loop retainer for use with a looping machine comprising a throat and an end portion adjacent said throat and extending upwardly therefrom, the forward edge of said portion receding from the upper edge thereof.

8. A loop retainer for use with a looping machine comprising a throat and an end portion adjacent said throat and extending upwardly therefrom, the forward edge of said portion receding from the upper edge thereof on a curved line.

9. A loop retainer, for use with a looping machine, comprising an end portion that is thin and flat, being thus adapted to extend between the end points of a foldable point carrier and to present a forward edge to the fabric impaled on the points.

10. A loop retainer, for use with a looping machine, comprising an end portion of considerably greater height than thickness, being thus adapted to extend between the end points of a foldable point carrier and to present a forward edge to the fabric impaled on the points.

11. In a looping machine in which there is a point carrier foldable to bring the points of the parts thereof into register to permit doubling of the loops by a stripper mechanism automatically movable to stripping position when said carrier is folded, a loop retainer and means for automatically putting the retainer in position to hold the fabric on the carrier points during folding.

12. In a looping machine in which there is a point carrier foldable to bring the points of the parts thereof into register to permit doubling of the loops by a stripper mechanism automatically movable to stripping position when said carrier is folded, a loop retainer and means for automatically putting the retainer in position to hold the fabric on the carrier points during folding, and means for automatically moving said retainer from said position for the stripping operation.

13. In a looping machine in which there is a point carrier foldable to bring the points of the parts thereof into register to permit doubling of the loops by a stripper mechanism automatically movable to stripping position when said carrier is folded, a loop retainer and means for automatically putting the retainer in position to hold the fabric on the carrier points during folding, and means operable by the movement of the stripper mechanism toward stripping position for moving said retainer from its functioning position and for holding it therefrom during the stripping operation.
14. In a looping machine in which there is a point carrier foldable to bring the points of the parts thereof into register to permit doubling of the loops by a stripper mechanism automatically movable to stripping position when said carrier is folded, loop retainers for holding the fabric on the carrier points during folding and an arm for each retainer, said arms normally holding said retainers away from said carrier but being swingable to put the retainers in position between the end points of the carrier parts and laterally movable to remove the retainers from said position during stripping.
15. In a looping machine in which there is a point carrier foldable to bring the points of the parts thereof into register to permit doubling of the loops by a stripper mechanism automatically movable to stripping position when said carrier is folded, loop retainers for holding the fabric on the carrier points during folding and an arm for each retainer, said arms being pivoted and laterally movable along their pivots, in combination with means for swinging said arms and a wedge between said arms and moved by said stripping mechanism to separate said arms.
16. In a looping machine in which there is a point carrier foldable to bring the points of the parts thereof into register to permit doubling of the loops by a stripper mechanism automatically movable to stripping position when said carrier is folded, loop retainers for holding the fabric on the carrier points during folding and an arm for each retainer, said arms normally holding said retainers away from said carrier but being swingable to put the retainers in position between the end points of the carrier parts and laterally movable to remove the retainers from said position during stripping, in combination with means for swinging said arms and a means associated with said stripper mechanism for controlling the lateral movement of said arms.
17. In a looping machine, a foldable point carrier and mechanism for folding it, a stripper mechanism, loop retainers and mechanism for putting said retainers in functioning position with respect to said carrier, in-

terrelated cam means for controlling the operations of said mechanisms in predetermined sequence and means controlled by said stripper mechanism for removing said retainers from said functioning position during the stripping operation.

18. In combination in a looping machine, a point carrier foldable to bring the points of one part thereof into register with the points of the other part, retainers for holding the fabric loops on the end points of said parts during folding, means for moving said retainers to functioning position with respect to said end points prior to folding of said point carrier and for moving them away from said position upon unfolding of said carrier, a stripper mechanism for doubling the loops on one part of said carrier onto the other part thereof while said carrier is folded, and means operable by the movement of the stripper mechanism toward and away from its operative position for causing said retainers to move respectively out of and into their functioning position.

19. In a looping machine, a foldable point carrier and mechanism for folding it, a stripper mechanism, loop retainers and mechanism for manipulating them, a cam drum for controlling the operations of said mechanisms in predetermined sequence, and a latch, said retainer manipulating mechanism comprising a lever engaging the cam drum, and said cam drum comprising a cam for moving said lever into engagement with said latch to cause said retainers to move to and to be held in functioning position with respect to the point carrier, and a second cam for releasing said lever from said latch.

In testimony whereof we have signed our names to this specification.

LOUIS N. D. WILLIAMS.
